Merrill E. Clark

UNITED STATES PATENT OFFICE.

LOUIS B. LOVEJOY, OF BRIDGEPORT, CONNECTICUT, ASSIGNOR, BY MESNE ASSIGNMENTS, TO CLARK METAL PRODUCTS, INCORPORATED, OF BRIDGEPORT, CONNECTICUT, A CORPORATION OF CONNECTICUT.

FLOOR AND CEILING PLATE FOR PIPES.

Application filed April 1, 1926. Serial No. 99,050.

This invention relates to floor or ceiling plates for pipes, that is, such plates as are customarily used, for example, upon exposed heating pipes in buildings, where they pass through the floors and ceilings. A plate of this kind should be attractive in appearance, easy and cheap to make, and easy to apply. And when applied it should grip the pipe firmly and remain securely in position.

10 The object of my present invention is to provide a plate of this character, which shall embody all of the above mentioned requirements to a more marked degree than has been attained by any such plates of which I am aware.

The manner in which this object is attained will now be set forth in detail.

In the drawing Fig. 1 is a top, plan view of my improved plate, as it appears when in position on a pipe; Fig. 2 is a similar view, with the parts separated, as is done, for example, in applying the plate to a pipe; Fig. 3 is similar to Fig. 2 except that it shows the bottom instead of the top; and Fig. 4 shows 25 one of the two semi-circular halves of which the plate is formed.

Referring to the drawing, it will be noted that the plate proper consists of two duplicate semi-circular halves 1, 2, each provided 30 with a semi-circular opening 3, 4, on the inside, the outer and inner edges of each half being preferably rolled as indicated at R, in order that they may present a neat appearance.

Referring now to the semi-circular half 1, for example, it will be seen that it is provided with an extension at each end, the one marked 35 1^f being a flush, rounded extension, and the one marked 1^d being depressed and being provided with a sloping guide edge 1^g, the purpose of which will be explained more 40 fully in a moment. The semi-circular half 2 is an exact duplicate of 1, the parts 2^f, 2^d and 2^g corresponding to 1^f, 1^d and 1^g.

45 As appears most clearly from Fig. 4, the flush extension 1^f is punched and drawn to form an eyelet shank 1^e. The depressed extension is punched with a hole 1^h of such a size that the eyelet shank 2^e of the half 2 will fit within it. Similarly the eyelet shank 1^e is adapted to fit into the hole 2^h of the half 2.

The assembling of the two halves is a very simple and inexpensive operation. It con-

sists simply in placing the eyelet shank 1^e, for example, into the hole 2^h, and then heading 55 over the eyelet shank, with the result that a sturdy hinged joint is formed. The other eyelet shank is not headed but left in its original form, so that when the two halves are closed up into the position shown in Fig. 1 60 this other eyelet shank 2^e will ride upon the guide 1^g and then spring into the hole 1^h, thus holding the two halves securely together. To open them up again it is necessary merely to 65 separate the end 2^f laterally from the end 1^d sufficiently to disengage the eyelet shank 2^e from the hole 1^h, when the parts may be 70 swung apart freely about the hinge formed as above described. The depressed extensions 1^d and 2^d are depressed sufficiently so that 75 the flush extensions 2^f and 1^f and the plates 1 and 2 themselves, will lie flush and in the same plane, when the parts are in the position of Fig. 1.

It is customary to provide plates of this 75 character with spring means for gripping the pipe when the plate is in position. My plate as described above may be provided with any 80 spring means suitable for this purpose. However, I prefer to use the particular spring devices illustrated at S in the drawing. As there appears, there is one of these devices in each semi-circular half. Each device consists of a V-shaped, or cotter-pin-shaped spring, 85 the head of which is adapted to be inserted in a small slot in the rolled over inner edge of the semi-circular half, so that the spring ends 90 embrace the pipe when the plate is in position.

The particular novelty in these spring 90 devices resides in the cross-sectional form of the 95 spring strips of which they are made. That is, as shown in the drawing these strips are concave in cross-section. The result is that instead of gripping the pipe with a smooth, flat surface, as is usually the case, the gripping 100 action of these strips is concentrated in the sharp edges. I have found that this gives a very much firmer grip than is otherwise possible, and that the plate can be slid along the pipe only by the application of considerable force. Thus the use of these spring devices upon plates of this character insures their remaining in position.

From the above description it is obvious 105 that the manufacturing operations involved

in the manufacture and assembling of my improved plate are extremely simple and inexpensive. In the first place, it is important to note that the manufacture is simplified 5 by the fact that the two halves are identical, requiring but a single die. And in the second place, I wish to stress the ease of assembling, this operation consisting merely in heading one of the eyelet shanks.

10 In the claims, where the words "down" or "up" are used, I am treating the plate as a floor-plate, so that "down" means toward the floor. I have adopted this method of expression as a matter of convenience only, and 15 not by way of limitation.

The terms and expressions which I have employed are used as terms of description and not of limitation, and I have no intention, in the use of such terms and expressions, of excluding any mechanical equivalent of the 20 features shown and described, or portions thereof, but recognize that various modifications are possible within the scope of the invention claimed.

25 What I claim is:

1. In a floor and ceiling plate structure for pipes, two identically formed semi-circular members, an extension lug formed integrally with one end of each member, a depressed 30 seat formed in the other end of each member to closely fit the complementary formed extension lug, and a hinge connection between the lug of one member and the depressed seat of the other member, the fitted relation of the 35 lug and the seat causing the parts to snap into locked relation when the members are moved to circle closing position, the extension lug of each member being provided with an opening and said depressed seat portion of 40 each member being provided with an eyelet shank whereby the eyelet shank of one member is adapted to provide a hinge pin and the eyelet shank of the other member is adapted to provide a latching member for engagement 45 with the opening in the depressed seat of the other member.

2. A device of the character described, comprising a pair of identically formed and interchangeable semi-circular members, each 50 member having an opening at one end and a downwardly extending eyelet shank at the other, one of said eyelet shanks being permanently retained in the opening in the other member by being headed over, thereby securing those ends of the members pivotally 55 together, the other eyelet shank being adapted to fit into the other opening for detachably holding the other ends of the members together, the member which has the opening 60 into which the shank is adapted to fit de-

tachably being provided with a guide for guiding said shank into said opening.

3. A device of the character described, comprising a pair of identically formed and interchangeable semi-circular members, each 65 member having at one end a flush extension provided with a downwardly extending eyelet shank, and at the other with a depression provided with an opening, the flush extension of each member being adapted to rest in the 70 depression of the other member, with the eyelet shank passing through said opening, one of said eyelet shanks being permanently retained in the opening by being headed over, thereby securing those ends of the members 75 pivotally together, the other eyelet shank and its opening serving as a detachable connection for the other ends of the members, the member which has the opening into which the shank is adapted to fit detachably being 80 provided with a guide for guiding said shank into said opening.

4. A device of the character described, comprising a pair of semi-circular members, each member having an opening at one end 85 and a downwardly extending eyelet shank at the other, one of said eyelet shanks being permanently retained in the opening in the other member by being headed over, thereby securing those ends of the members pivotally 90 together, and the other eyelet shank being adapted to fit into the other opening for detachably holding the other ends of the members together, each of said members being provided on the interior with a bifurcated 95 spring having concave surfaces arranged to present double edges for frictionally engaging a pipe encircled by said members.

5. A device of the character described, comprising a pair of semi-circular members, 100 each member having at one end a flush extension provided with a downwardly extending eyelet shank, and at the other with a depression provided with an opening, the flush extension of each member being adapted to 105 rest in the depression of the other member, with the eyelet shank passing through said opening, one of said eyelet shanks being permanently retained in the opening by being headed over, thereby securing those ends of 110 the members pivotally together, the other eyelet shank and its opening serving as a detachable connection for the other ends of the members, each of said members being provided on the interior with a bifurcated spring 115 having concave surfaces arranged to present double edges for frictionally engaging a pipe encircled by said members.
